CLAIM

The ornamental design for an alarm clock with wireless charging function, as shown and described.

DESCRIPTION

FIG. 1 is a top, rear and left side perspective view of an alarm clock with wireless charging function showing my new design;

FIG. 2 is a bottom, front and right side perspective view thereof;

FIG. 3 is a rear elevational view thereof;

FIG. 4 is a front elevational view thereof;

FIG. 5 is a right side view thereof;

FIG. 6 is a left side view thereof;

FIG. 7 is a top plan view thereof;

FIG. 8 is a bottom plan view thereof;

FIG. 9 is an enlarged view of the portion as defined by the circle 9 in FIG. 2; and,

FIG. 10 is a top, front and right side perspective view showing the alarm clock with wireless charging function in a use state.

The broken lines shown in the drawings depicting portions of the alarm clock with wireless charging function in FIGS. 1-10 form no part of the claimed design. The broken lines shown in the drawings depicting a cell phone in FIG. 10 illustrate environment and form no part of the claimed design.

1 Claim, 10 Drawing Sheets
